UNITED STATES PATENT OFFICE.

JAMES R. RICKETTS, OF KINGFISHER, OKLAHOMA TERRITORY, ASSIGNOR
OF ONE-HALF TO GEORGE W. WILSON, OF KINGFISHER, OKLAHOMA
TERRITORY.

COMPRESSED-AIR WATER-ELEVATOR.

SPECIFICATION forming part of Letters Patent No. 697,171, dated April 8, 1902.

Application filed December 3, 1901. Serial No. 84,561. (No model.)

To all whom it may concern:

Be it known that I, JAMES R. RICKETTS, a citizen of the United States, residing at Kingfisher, in the county of Kingfisher, Territory of Oklahoma, have invented certain new and useful Improvements in Compressed-Air Water-Elevators, of which the following is a specification, reference being had therein to the accompanying drawing.

10 This invention relates to a compressed-air water-elevator, and particularly to an escape mechanism for permitting the escape of compressed air from the vessel after the raising of liquid thereby.

15 The invention has for its object to provide an improved construction of escape mechanism adapted to be automatically operated by the entrance and discharge of water from the vessel and to permit a preliminary escape of 20 air therefrom before the opening of the main escape-valve.

A further object of the invention is to provide an improved construction of escape-valve carried by the stem of an inlet-valve 25 and adapted to effect an air-tight closure under tension upon its seat in the closing action of the inlet-valve.

Other and further objects and advantages of the invention will be hereinafter set forth 30 and the novel features thereof particularly defined by the appending claims.

The drawing represents a vertical section through a vessel containing the operative parts of this invention.

35 In the drawing the letter A designates a vessel or tank of any suitable construction and configuration and adapted to be submerged in the liquid to be raised and supported therein above the bottom of the liquid. This vessel is provided with a bottom plate A', having an inlet-aperture A², and with a top plate A³, formed to receive the several connecting-pipes hereinafter described.

40 This top plate is also provided with a valve-chamber A⁴, connected thereto by a neck A⁵, which chamber is formed at its upper end with a vent-pipe A⁶, extending above the body of the liquid in which the vessel is submerged. The normal level of this liquid is indicated 45 by a dotted line a a in the drawing and the

filling-level within the vessel by the dotted line b b. Cooperating with the inlet-opening A² a valve B is provided and has a vertically-disposed stem B' extending upward through the vessel and neck A⁵ into the valve-case A⁴, 55 where it is provided with an escape-valve B², adapted to seat upon the upper end of the neck A⁵. This valve is slidably mounted upon the stem and normally held in contact with a nut B³ thereon by means of a tension-spring B⁴, extending between the upper face of the valve, and an adjusting-nut B⁵, by means of which the tension of the spring may be regulated. The valve-rod B' is guided by means of a stop-arm A⁶ at the lower portion 60 of the vessel, and a spider-frame A⁷ disposed within the neck. The relative positions of the escape and inlet valves is such that the escape-valve seats before the inlet-valve completely closes, and the continued movement 65 of the latter places the spring above the escape-valve under tension to firmly secure an air-tight seating of the escape-valve. Communicating with the valve-casing B⁴ is a vent-pipe B⁶, extending into the upper portion of 70 the vessel A and there provided with a stop-cock B⁷, which is provided with a lever B⁸. For the purpose of operating this lever in the rising and falling action of the water in the vessel a rod B⁹ is connected therewith and 75 provided with a float B¹⁰, which in its lowered position rests upon the guide-lug B¹¹.

For the purpose of introducing air under pressure in the vessel A a conducting-pipe C is provided and connected at its upper end 85 C' with any suitable source of supply, such as an air-pump, while at the lower end thereof a stop-cock C² is attached and provided with an operating-lever C³, connected by a link C⁴ and adjustable clamps C⁵ to the stem B'. By 90 this means the connection of the air-valve with the stem may be adjusted to determine the proper time for opening the same.

For the purpose of conveying the water or liquid from the vessel a discharge-pipe D is 95 provided and extends to the lower portion of the vessel, where an automatically-acting valve, such as a check-valve D', is located to permit the entrance of water into the pipe and preventing the discharge therefrom at 100

any time. The upper portion D² of this pipe is connected with any suitable discharge means as may be found desirable.

In the operation of the invention with the 5 parts in the position shown in the drawing the air-inlet valve is closed, while the escape-valve and vent-pipe are open, thus permitting the escape of the air-pressure within the vessel and the free inlet of water thereto. 10 As the water-level in the vessel rises the float B¹⁰ is carried upward, thus closing the vent-pipe, and the water continues to rise until the pressure is equalized and approximately the level b b is reached. The buoyant force 15 of the liquid surrounding the vessel when empty raises the valve B, which valve closes by gravity after the vessel has become filled, and in its closing action operates the air-inlet valve C² to permit the entrance of compressed air, the pressure of which retains 20 the valve B in a closed position. It will be seen that the inward pressure is the same in all directions within the vessel and the escape-valve being of less area than the inlet- 25 valve and outside of the vessel. Therefore if these valves be connected by the stem B' the increase of the inward pressure within the vessel will retain them in a closed position so long as it is kept up. When all the liquid 30 has been forced upward through the discharge D, the float again descends to the full-line position, thus opening the vent-pipe and lowering the pressure within the vessel, so as to permit the inlet and escape valves to open 35 and admit more liquid, as just described. It will be noted that when the vessel is completely filled the vent-cock B' is closed and the further escape of air occurs through the escape-valve. As before described, this escape-valve reaches its seat slightly before the inlet-valve, and the remaining motion of the latter places the escape-valve under tension to hold it firmly in air-tight contact with its seat. The shifted position of the valves just 45 described is shown by dotted lines in the drawing.

It will be obvious that changes may be made in the details of construction and configuration without departing from the spirit 50 of the invention as defined by the appended claims.

Having described my invention and set forth its merits, what I claim, and desire to secure by Letters Patent, is—

55 1. The combination with a water vessel, of an air-pipe connected therewith, a liquid-discharge extending from the lower portion of the vessel, an escape-pipe extending from the upper portion of the vessel, an inlet-valve 60 having a stem extending upwardly therefrom, and an escape-valve movable simultaneously with said inlet-valve and adapted to reciprocate upon said stem to close said escape-pipe before the seating of the inlet-valve; substantially as specified.

65 2. The combination with a water vessel, of an air-pipe connected therewith, a liquid-dis-

charge extending from the lower portion of said vessel, an escape-pipe extending from the upper portion of said vessel, an inlet-valve 70 having a stem extending upwardly therefrom, an escape-valve movably mounted upon said stem, a vent-pipe communicating with said escape-pipe above the escape-valve, and means for automatically opening and closing 75 said vent-pipe; substantially as specified.

3. The combination with a water vessel, of an air-pipe connected therewith, a liquid-discharge extending from the lower portion of said vessel, an escape-pipe extending from the 80 upper portion of said vessel, an inlet-valve having a stem extending upwardly therefrom, an escape-valve movably mounted upon said stem, a vent-pipe communicating with said escape-pipe above the escape-valve, means for 85 automatically opening and closing said vent-pipe, an inlet-cock for said air-pipe, and a connection between said cock and valve-stem for automatically operating the former; substantially as specified. 90

4. The combination with a water vessel, of an air-pipe communicating therewith, a liquid-discharge extending from the lower portion thereof, an air-escape valve in the upper portion, an inlet-valve adapted to automatically operate said escape-valve, and a vent 95 adapted to permit the escape of air from the vessel before the opening of the inlet and escape valves; substantially as specified.

5. The combination with a water vessel, of an air-pipe communicating therewith, a discharge-pipe extending from the lower portion thereof, an escape-pipe communicating with the top of said vessel and provided with a valve-chamber therein, an inlet-valve at the 100 lower portion of said vessel, a valve-stem extending upward from said valve, and an escape-valve carried by said stem and adapted to seat before the seating of the inlet-valve; substantially as specified. 110

6. The combination with a water vessel, of an air-pipe communicating therewith, a discharge-pipe extending from the lower portion thereof, an escape-pipe communicating with the top of said vessel and provided with 115 a valve-chamber therein, an inlet-valve at the lower portion of said vessel, a valve-stem extending upward from said valve, an escape-valve carried by said stem and adapted to seat before the seating of the inlet-valve, a 120 stop-nut on said stem to limit the downward movement of said escape-valve, and an adjustable spring for retaining said escape-valve in yielding contact with said nut; substantially as specified. 125

7. The combination with a water vessel, of an air-pipe communicating therewith, a discharge-pipe extending from the lower portion thereof, an escape-pipe communicating with the top of said vessel and provided with a 130 valve-chamber therein, an inlet-valve at the lower portion of said vessel, a valve-stem extending upward from said valve, an escape-valve carried by said stem and adapted to

seat before the seating of the inlet-valve, a stop-nut on said stem to limit the downward movement of said escape-valve, an adjustable spring for retaining said escape-valve in yielding contact with said nut; a stop-cock upon said air-pipe, and an operating-rod for said cock adjustably connected to said valve-stem; substantially as specified.

8. The combination with a water vessel, of an air-pipe communicating therewith, a discharge-pipe extending from the lower portion thereof, an escape-pipe communicating with the top of said vessel and provided with a valve-chamber thereon, an inlet-valve at the lower portion of said vessel, a valve-stem extending upward from said valve, an escape-valve carried by said stem and adapted to seat before the seating of the inlet-valve, a stop-nut on said stem to limit the downward movement of said escape-valve, an adjustable spring for retaining said escape-valve in yielding contact with said nut, a vent-cock upon said air-pipe, an operating-rod for said cock adjustably connected to said valve-stem, a vent-pipe extending from said valve-casing into said vessel and provided with a stop-cock thereon, and a float for closing said vent-cock; substantially as specified.

9. The combination with a water vessel, of an air-pipe communicating therewith, a discharge-pipe extending from the lower portion thereof, an escape-pipe communicating with the top of said vessel and provided with a valve-chamber thereon, an inlet-valve at the lower portion of said vessel, a valve-stem extending upward from said valve, an escape-valve carried by said stem and adapted to seat before the seating of the inlet-valve, a stop-nut on said stem to limit the downward movement of said escape-valve, an adjustable spring for retaining said escape-valve in yielding contact with said nut, a stop-cock upon said air-pipe, an operating-rod for said cock adjustably connected to said valve-stem, a vent-pipe extending from said valve-casing into said vessel and provided with a vent-cock thereon, a float for closing said vent-cock, a connecting-neck between said vessel and valve-case having its upper end forming a valve-seat for the escape-valve; substantially as specified.

In testimony whereof I affix my signature in presence of two witnesses.
